CARRYING AND STORAGE CASE FOR PAINTERS' MATERIALS OR THE LIKE

James D. Jolly, McQuady, Ky. 40153

Filed Apr. 10, 1973, Ser. No. 350,612

Term of patent 14 years

Int. Cl. D3—02

U.S. Cl. D87—1 R

FIG. 1 is a front, top and left side perspective view of a carrying and storage case for painters' materials or the like showing my new design;

FIG. 2 is a top plan view;

FIG. 3 is a left side elevational view;

FIG. 4 is a bottom plan view;

FIG. 5 is a front elevational view; and

FIG. 6 is a rear elevational view.

I claim:

The ornamental design for a carrying and storage case for painters' materials or the like, as shown and described.
